UNITED STATES PATENT OFFICE.

CHARLES C. HANSEN, OF EASTON, PENNSYLVANIA, ASSIGNOR TO INGERSOLL-RAND COMPANY, OF NEW YORK, N. Y., A CORPORATION OF NEW JERSEY.

OILER.

1,109,222.

Specification of Letters Patent.

Patented Sept. 1, 1914.

Original application filed May 16, 1910, Serial No. 561,715. Divided and this application filed August 13, 1910. Serial No. 577,030.

To all whom it may concern:

Be it known that I, CHARLES C. HANSEN, a citizen of the United States, and resident of Easton, in the county of Northampton and State of Pennsylvania, have invented a new and useful Improvement in Oilers, of which the following is a specification.

This invention comprises a novel oiler intended to be used in connection with a pressure fluid operated engine, such, for instance, as a rock drill, the said oiler comprising an oil impregnated cartridge located in position to have the oil extracted therefrom in small quantities by variations in the fluid pressure due to the operation of the engine.

Practical embodiments of this invention are represented in the accompanying drawings, in which—

Figure 1 represents the oiler as located in the fluid pressure supply passage between the pressure fluid controlling valve and the valve chest of the engine, certain of the parts being shown in side elevation and certain of the parts in section, Fig. 2 is a similar view showing the oiler located directly in the valve chest, Fig. 3 is a detail sectional view showing the oiler located in a passage in communication with the interior of the valve chest of the engine, Fig. 4 is a detail side view of one form of cartridge receiving shell, Fig. 5 represents the several parts of the cartridge disassembled, Fig. 6 is a perspective view of the cartridge carrying box used for transportation purposes, a portion of the same being broken away to show a cartridge located therein, and Fig. 7 is an enlarged detail cross section through the cartridge body to more clearly illustrate its structure.

The cartridge proper comprises a body 1 and its carrying pin 2, screw plug 3 and means for securing the body 1 on the pin 2, in the present instance comprising washers 4 and cotter pin 5. The body portion 1 is arranged to be impregnated with the lubricating oil, which body portion is herein shown as comprising a strip of fabric such as flannel or cotton and a strip of brass wire netting rolled together around the pin 2. By this arrangement a porous mass is provided which will contain a considerable amount of lubricating oil. This cartridge is introduced into a chamber or passage in communication with the pressure fluid sup-

ply for operating the engine so as to be subjected to the fluctuations in pressure or, in other words, the pulsations due to the operation of the engine. This introduction of the oil impregnated cartridge into communication with the fluid pressure supply for the engine may be accomplished in various ways, several of which are herein illustrated and will be now described.

Referring to Fig. 1, a hollow coupling 6 is connected to the fluid pressure supply pipe 7 and valve chest 8 of the engine. The fluid pressure supply pipe 7 is provided with the usual fluid pressure controlling valve 9. A hollow shell 10 is screwed into the coupling 6. This hollow shell is provided with one or more openings 11 at its inner end within the coupling 6 for bringing the interior of the shell into open communication with the interior of the coupling 6. The cartridge is inserted into the shell 10 and held in its position therein by the screw threaded engagement of the plug 3 with the outer end of the shell 10.

In Fig. 2, the cartridge, with a slightly modified form of shell 10, is inserted into the valve chest 8. The hole 11 in the shell 10, is, in this instance, in communication with the motive fluid inlet passage 12 of the valve chest.

In Fig. 3 the shell 10 is disposed of and the cartridge is inserted into a chamber 13 in open communication with the interior of the valve chest through a port 14.

In operation, the cartridge is soaked in oil until it has become thoroughly impregnated therewith. The cartridge is then inserted into position to bring it in communication with the pressure fluid for operating the engine. This may be done in the manner shown in Figs. 1 and 2, by inserting the cartridge into a shell and inserting the shell into the pressure fluid supply passage or it may be accomplished by inserting the cartridge itself without its shell into a chamber in communication with the fluid pressure supply passage, as in Fig. 3.

When the engine is running, there are fluctuations in pressure, or, in other words, pulsations in the pressure fluid supply passage due to the slightly reduced fluid pressure when the engine takes the full charge of the motive fluid at the beginning of its stroke. These pulsations in the fluid pres-

sure supply passage will extract oil little by little from the cartridge thus obtaining a continuous supply of oil in the desired quantities for the engine while the engine is running.

In actual practice, the proper lubrication of the engine may be insured by the fact that it can be readily determined how long one oil impregnated cartridge will last in the engine. For instance, if the operator of the engine is given three of these oil impregnated cartridges for operating the engine a predetermined time and he should not return all three of these cartridges in their dry condition after the engine has been run the predetermined time, then the engine has not been properly supplied with its lubricating oil, as there is only one way that these oil impregnated cartridges can be run dry and that is by actually inserting them into the fluid pressure supply passage where they can be subjected to the pulsations due to the operation of the engine. A further very beneficial result by the use of these oil impregnated cartridges is that a surplus of oil cannot possibly be supplied to the engine. This will insure an enormous saving in oil and thereby expense in the operation of the engine. This economical method of supplying oil to the engine will also permit the machine to be used successfully in connection with rock drills for operating on free milling gold properties where the waste of oil on the rock will materially reduce the amalgamation, as the quantity of oil used with my improved oiler is so small that it will not be sufficient to affect the mercury on the plates in this work. It is desirable that means be employed for transporting these cartridges. I therefore employ suitable boxes 15, each arranged to contain a cartridge.

The parts shown and described but not claimed herein, form the subject matter of a co-pending application filed by me the

sixteenth day of May, 1910, serial No. 561,715, of which this case is a division.

What I claim is:

1. An oil distributing cartridge comprising a strip of oil absorbing material and a strip of wire gauze rolled together to form a porous mass.

2. An oil distributing cartridge comprising a plug, a pin projecting therefrom, a strip of oil absorbing material and a strip of wire gauze rolled together around said pin to form a porous mass.

3. An oil distributing cartridge comprising a plug, a pin projecting therefrom, a strip of oil absorbing material and a strip of wire gauze rolled together around said pin to form a porous mass and means for securing said porous mass in position on the pin.

4. An oil distributing cartridge comprising a screw threaded plug, a pin projecting therefrom, a strip of oil absorbing material and a strip of wire gauze rolled together around said pin to form a porous mass and means engaging the pin for securing the porous mass in position thereon.

5. An oil distributing cartridge for a fluid pressure supply passage comprising a hollow shell arranged to project into said supply passage, a plug removably secured to the shell and an exposed porous body portion secured to the plug and projecting into said hollow shell, the hollow shell being provided with one or more openings for bringing the said porous body portion into open communication with the fluid pressure supply passage.

In testimony, that I claim the foregoing as my invention, I have signed my name in presence of two witnesses, this 10th day of August 1910.

CHARLES C. HANSEN.
